(57) **CLAIM**

The ornamental design for a caddy, as shown and described.

DESCRIPTION

FIG. 1 is a perspective view of a caddy showing a first embodiment of our new design with a hook placed in a first position.

FIG. 2 is a front elevation view of the caddy of FIG. 1.

FIG. 3 is a back elevation view of the caddy of FIG. 1.

FIG. 4 is a right elevation view of the caddy of FIG. 1.

FIG. 5 is a left elevation view of the caddy of FIG. 1.

FIG. 6 is a top plan view of the caddy of FIG. 1.

FIG. 7 is a bottom plan view of the caddy of FIG. 1.

FIG. 8 is a perspective view of a caddy showing the first embodiment of our new design with the hook placed in a second position.

FIG. 9 is a front elevation view of the caddy of FIG. 8.

FIG. 10 is a back elevation view of the caddy of FIG. 8.

FIG. 11 is a right elevation view of the caddy of FIG. 8.

FIG. 12 is a left elevation view of the caddy of FIG. 8.

FIG. 13 is a top plan view of the caddy of FIG. 8; and,

FIG. 14 is a bottom plan view of the caddy of FIG. 8.

The broken line showing in the figures is included for the purpose of illustrating portions of the article and forms no part of the claimed design.

1 Claim, 10 Drawing Sheets
